UNITED STATES PATENT OFFICE

ERNST ZINDEL, OF DESSAU, GERMANY, ASSIGNEE TO HUGO JUNKERS, OF DESSAU, GERMANY

FLYING BOAT

Application filed June 9, 1928, Serial No. 284,059, and in Germany February 17, 1928.

My invention refers to flying machines and more especially to that type which is called "flying boat" because the fuselage resembles the hull of a boat and is adapted to rest on and be partly immersed in the water. My invention has particularly reference to flying boats having two parallel fuselages in the form of boats' hulls, which are spaced symmetrically and in parallel to the middle axis of the craft. 5 Flying boats of the twin-hull type offer the advantage, as compared with single-hull machines, of presenting greater stability when floating on the water. On the other hand this type of flying boats involves a disadvantage, 10 which becomes apparent more particularly in twin-hull machines of the monoplane type with a self-supporting wing, in which the wing forms the only connection between the two hulls. This disadvantage consists therein 15 that the middle portion of the wing intermediate the two hulls is subjected to severe bending and torsional stresses by shocks, for instance the impact of waves acting on a hull from the side or when the buoyancy is not 20 evenly distributed on the two hulls, for instance in the case where the craft moves forward in oblique direction to high waves. 25

The present invention is concerned with means for increasing the resistivity of this 30 middle portion of the wing structure intermediate the two hulls. To this end I provide braces or struts secured to the bottom parts of the adjoining side walls of the two hulls, these braces or struts being either connected 35 with each other in fixed points underneath the girder connecting the two hulls, or in points forming part of the middle wing portion, so that this bracing structure assists the girder in taking up the stresses acting thereon. 40 I may arrange such bracing connections in a single transversal plane, but I prefer providing such structures in at least two transversal planes at a considerable distance from each other, as in this manner I obtain a more 45 efficient resistivity against torsional stresses. Preferably the ends of the struts fixed to the boats' hulls are secured to a middle hull arranged in the middle axis of the craft and projecting downwards from the wing without 50 acting as a floating body. I may however also

provide auxiliary structures below the bottom of the middle wing portion, the connecting points of such auxiliary structure serving for securing the inner ends of the struts fixed to the hulls. 55

In the drawings affixed to this specification and forming part thereof two flying boats embodying my invention are illustrated diagrammatically by way of example.

In the drawings
Fig. 1 is a vertical longitudinal section on the line I—I in Fig. 2, while
Fig. 2 is a front view and
Fig. 3 is a plan view of one modification.
Fig. 4 is a front view of another modification. 60 65

Referring to the drawings and more particularly to Figs. 1—3, 1 and 2 are the two hulls serving as floating bodies and 3 is a middle hull arranged between them without however extending down to the water surface. These three hulls are interconnected by a girder constituted by the middle portion of the self-supporting wing 4. In order to relieve this wing portion of the bending and torsional stresses arising more particularly in a heavy sea, struts 11, 12 extend from the bottom parts of the hulls 1, 2 to the bottom part of the middle hull 3. As shown in Figs. 1 and 3, two such bracing structures are provided 70 between the two hulls 1 and 2. 75

In the modification illustrated in Fig. 4, which is not provided with a middle hull projecting below the bottom of the wing, auxiliary bracing structures are provided below the wing bottom, consisting of struts 13 and horizontal braces 14. The struts 11 and 12 fixed to the boats' hulls 1, 2 are secured to the connecting points 15, 16 of the auxiliary bracing structure. 80 85

My invention may be applied with equal advantage also to compound machines of the amphibium type which form a combination of land and sea-plane and in which besides the floating bodies a separate landing carriage is provided. This modification is indicated in dotted lines in Figs. 1 and 2, which show a wheel 21, 22 arranged on each hull directly in front of the step 23, an auxiliary pike 24 being provided at the end of each hull. These 90 95 100

wheels and auxiliary pikes may be arranged to be folded up in a well known manner in order that the propulsion of the boats in the water be hindered as little possible.

6 I wish it to be understood that I do not desire to be limited to the exact details of construction shown and described for obvious modifications will occur to a person skilled in the art.

10 I claim:—

1. A flying boat of the monoplane twin-hull type, comprising a wing forming a continuous beam, two floating hulls adapted to carry the entire weight of the craft, said hulls being rigidly fixed to and extending below the bottom of said wing in spaced relation and substantially parallel to the longitudinal middle axis of the craft, and means spaced from said wing for bracing the adjoining side walls of said hulls against each other and for reinforcing the portion of said wing intermediate said hulls.

2. A flying boat of the monoplane twin-hull type, comprising a wing forming a continuous beam, two floating hulls adapted to carry the entire weight of the craft, said hulls being rigidly fixed to and extending below the bottom of said wing in spaced relation and substantially parallel to the longitudinal middle axis of the craft, and means spaced from said wing for bracing the adjoining side walls of said hulls against each other and against the middle portion of said wing and for reinforcing the portion of said wing intermediate said hulls.

3. A flying boat of the monoplane twin-hull type, comprising a wing forming a continuous beam, two floating hulls adapted to carry the entire weight of the craft, said hulls being rigidly fixed to and extending below the bottom of said wing in spaced relation and substantially parallel to the longitudinal middle axis of the craft, and struts spaced from said wing for bracing the adjoining side walls of said hulls against each other and for reinforcing the portion of said wing intermediate said hulls.

4. A flying boat of the monoplane twin-hull type, comprising a wing forming a continuous beam, two floating hulls adapted to carry the entire weight of the craft, said hulls being rigidly fixed to and extending below the bottom of said wing in spaced relation and substantially parallel to the longitudinal middle axis of the craft, and struts spaced from said wing for bracing the adjoining side walls of said hulls against each other and against the middle portion of said wing and for reinforcing the portion of said wing intermediate said hulls.

5. A flying boat of the monoplane twin-hull type, comprising a wing forming a continuous beam, two floating hulls adapted to carry the entire weight of the craft, said hulls being rigidly fixed to and extending below

the bottom of said wing in spaced relation and substantially parallel to the longitudinal middle axis of the craft, and means spaced from said wing and extending in two longitudinally spaced planes for bracing the adjoining side walls of said hulls against each other and for reinforcing the portion of said wing intermediate said hulls.

6. A flying boat of the monoplane twin-hull type, comprising a wing forming a continuous beam, two floating hulls adapted to carry the entire weight of the craft, said hulls being rigidly fixed to and extending below the bottom of said wing in spaced relation and substantially parallel to the longitudinal middle axis of the craft, and struts spaced from said wing and extending in two longitudinally spaced planes for bracing the adjoining side walls of said hulls against each other and against the middle portion of said wing and for reinforcing the portion of said wing intermediate said hulls.

7. A flying boat of the monoplane twin-hull type, comprising a wing forming a continuous beam, two floating hulls adapted to carry the entire weight of the craft, said hulls being rigidly fixed to and extending below the bottom of said wing in spaced relation and substantially parallel to the longitudinal middle axis of the craft, and means for bracing the adjoining side walls of said floating hulls against each other and against the middle portion of said wing, said means including a hull extending below the bottom of said wing intermediate said floating hulls.

In testimony whereof I affix my signature.
ERNST ZINDEL.
